UNITED STATES PATENT OFFICE.

FLOYD C. ATKINSON, OF WESTERN PORT, MARYLAND.

TIP FOR CRUTCHES AND CANES.

Application filed July 19, 1926. Serial No. 123,551.

This invention relates to improvements in tips for crutches, canes, and the like, and has as its general object to provide a tip which will possess decided advantages over 5 rubber tips such as have heretofore been employed.

The ordinary crutch tip has a roughened under surface but in a short while this surface becomes so worn that it is liable to 10 slip on wet street surfaces and does not give the user the feeling of safety which is desirable in devices of this class. Therefore, it is one of the objects of the present invention to provide a crutch tip which will, 15 when weight is imposed thereon, tend to adhere to the surface upon which it is disposed and which will, at the same time, afford an increased degree of resiliency in contacting and leaving the surface so that 20 one using a crutch or cane equipped with the tip may use the same with comfort and without the annoyance of the transmitted impacts which attend the use of ordinary tips.

Another objection which is inherent in 25 crutch tips of the ordinary construction is that they are fitted over the end of the crutch or cane staff, as the case may be, and in a short period of time the said end of the 30 staff of the crutch or cane will work its way through the tip, thus requiring replacement of the tip. Therefore, it is another object 35 of the present invention to overcome this disadvantage by providing a tip in the construction of which means is provided for 40 effectually preventing any penetration of the tip by the end of the crutch or cane staff.

Another disadvantage presented by the 45 ordinary crutch tip is that it is fitted over 50 the end of the crutch staff and held solely by friction so that the tip is liable to be pulled off from the staff if it becomes caught in any obstruction and, therefore, it is another important object of the present invention 55 to provide a crutch tip which will comprise a complete unit for attachment to the plain cylindrical end of a crutch staff or of a cane, and which will be so constructed that it will be substantially permanently 60 united to the said staff and cannot be removed therefrom without considerable force being imposed thereon.

In the accompanying drawings:

Figure 1 is a perspective view of a crutch 65 equipped with the tip embodying the invention.

Figure 2 is a detail vertical sectional view through the tip.

Figure 3 is a horizontal sectional view taken substantially on the line 3—3 of Figure 2, looking in the direction indicated by the arrows.

In the drawings, the numeral 1 indicates the staff of a crutch or cane which does not differ in its contour or construction from 65 common practice except that, for a purpose to be presently explained, it is provided with a transverse opening 2 adjacent its lower extremity. The tip embodying the 70 invention includes a ferrule which is indicated by the numeral 3 and which has a cylindrical bore 4 into which the lower end of the staff of the crutch or cane is snugly and tightly fitted. The upper portion of the ferrule may be comparatively small in 75 diameter but the lower portion is preferably flared outwardly to provide a circumscribing shoulder 5 having a flat under face indicated by the numeral 6. The face 6 is spaced above the lower end of the ferrule 80 and the said lower end of the ferrule is preferably in registration with the extreme lower end of the staff of the crutch or cane. Below the shoulder 6, the ferrule of the 85 tip is exteriorly cylindrical, providing an anchoring portion which is indicated by the numeral 7 and which is formed exteriorly at its lower extremity with a circumferential outstanding bead 8 spaced from the said shoulder 6. A pin 9 is driven diametrically 90 through the opening 2 in the lower end of the staff of the crutch or cane to which the ferrule 3 is fitted and through openings 10 formed at diametrically opposite points in the portion 7 of the ferrule, the ends of the 95 pin being flush with the exterior surface of the said portion 7. In this manner the ferrule is securely and permanently connected with the lower end of the staff of the crutch or cane and securely held in place. 100

The cushioning element of the crutch tip is indicated by the numeral 11 and the same comprises an approximately cylindrical body of relatively soft rubber having a socket 12 formed in its upper end and of dimensions and contour to very snugly receive the portion 7 of the said ferrule and the bead 8 which is formed thereon, this socket, for the latter purpose, being provided at its bottom with an enlargement or annular recess which is indicated by the numeral 13. The lower end of the body 11 is of concave 110

form as indicated by the numeral 14, so that the rim of this portion will engage with the surface upon which the crutch or cane is disposed, in use, and due to the con-
 5 cave formation of the engaging surface of the elastic body, the crutch tip will, when weight is imposed thereon, grip the surface by suction to prevent slipping, and, like-
 10 wise, the crutch or cane is cushioned at the moment it is disposed upon the surface and likewise at the moment it leaves the surface. In this manner, a springy and lively contact is produced as the crutch or cane equipped with the tip contacts the surface upon which
 15 the user is walking, thereby materially lessening the jar which is ordinarily transmitted to the arm pit or hand of one using a crutch or cane.

It will be observed by reference to Figure 2 of the drawings, that the upper end of the cushioning member 11 squarely abuts the flat under face 6 of the shoulder 5 and that the upper end of the said cushioning member 11 is of a diameter approxi-
 25 mately equal to the diameter of the said shoulder so that there is no liability of the ferrule cutting into the rubber of which the said member 11 is formed. Likewise, due to the comparatively large area of surface
 30 contact of the face 6 of the shoulder 5 and the upper end of the body 11, there is no likelihood of the lower or bead carrying end of the ferrule cutting into the body of the cushioning member 11, so that in both in-
 35 stances the connection of the body 11 is such that the life of the said body is materially prolonged. It will also be evident that the engagement of the bead 8 upon the ferrule, in the annular recess 13 in the wall of the
 40 socket 12, serves to securely anchor the body 11 to the lower end of the ferrule and that as a consequence there is no likelihood of the cushioning body being torn loose from

the ferrule through contact with obstruc-
 45 tions which might be met with in the use of the crutch or cane equipped with the tip.

It will be noted that the ends of the pin
 9 are engaged by the wall of the socket in the cushioning member 11 of the tip so that the ends of the pin are prevented from com-
 50 ing in contact with any obstructions which might tend to drive the pin out of place.

Having thus described the invention, what I claim is:

1. A tip for crutches and the like comprising a ferrule having a bore to accom-
 5 modate the end of the crutch staff, a pin
 engaged transversely of the staff and fer-
 rule, the ferrule having a circumscribing
 shoulder having a flat under face, the por-
 60 tion of the ferrule below the shoulder being
 cylindrical and being provided at its lower
 end with a circumscribing anchoring bead,
 and a cushioning member having a socket
 65 accomodating the said portion of the fer-
 rule below the shoulder, the upper end of
 the said cushioning member abutting the
 under face of the shoulder and the wall of
 the socket in the cushioning member having
 70 a recess accomodating the anchoring bead,
 said pin being retained against endwise
 movement by the side walls of the socket.

2. The combination with the staff of a
 crutch or the like, of a tip comprising a fer-
 rule having a bore accomodating the end
 75 of the said staff, the staff and the wall of the
 bore having registering openings, a pin
 driven through the parts with its ends sub-
 stantially flush with the exterior of the fer-
 rule, and a cushioning member confining the
 80 lower end of the ferrule and covering the
 said ends of the pin.

In testimony whereof I affix my signature.

FLOYD C. ATKINSON. [L. S.]
